UNITED STATES PATENT OFFICE.

CHARLES B. HESTON, OF PHILADELPHIA, PENNSYLVANIA, ASSIGNOR TO
DAVID HESTON & SONS, OF SAME PLACE.

BOTTLE-PACKING.

SPECIFICATION forming part of Letters Patent No. 373,019, dated November 8, 1887.

Application filed September 5, 1887. Serial No. 248,835. (No model.)

To all whom it may concern:

Be it known that I, CHARLES B. HESTON, a citizen of the United States, residing in the city and county of Philadelphia, State of Pennsylvania, have invented a new and useful Improvement in Safety-Packing for Bottles, which improvement is fully set forth in the following specification and accompanying drawings.

10 My invention relates to improvements in packages or wrappers for bottles, whereby breakage of the same is prevented; and it consists in providing a jacket with a lining having ridges corresponding to the thickened portion of the bottle, substantially as hereinafter set forth.

Prior to my invention it was old in the art to pack bottles for transportation in crimped paper or pasteboard packing having numerous 20 crimps or ribs running lengthwise of the bottle and bearing against all portions thereof. Such a packing or protecting-lining, however, pressed with equal stress on all portions of the bottle and endangered the bottles by reason 25 of said pressure.

My invention avoids this objectionable feature, as will be better understood from the following description, taken in connection with the accompanying drawings, in which—

30 Figure 1 is a cross-section taken through a bottle packed in a box with my improved safety-packing. Fig. 2 is a similar section taken through a different form of bottle similarly packed. Fig. 3 is a plan view of my improved safety bottle-packing, showing the crimped or struck-up ribs.

Similar letters of reference indicate corresponding parts in the several figures.

Referring to the drawings, A is the bottle, B the packing-box, and C the improved safety-packing having ribs or indentations *a a*, adapted to bear against the stronger or thicker portions of the bottles, as at *b b*, or, if the bottle be of equal thickness, as shown, then at or in the angular parts, thus distributing 45 the strain.

In Fig. 3 I have shown the protector when developed or unrolled. It consists, usually, of pasteboard, and the ribs *a* are struck up in any well-known manner.

It will be understood that when the ribbed case has been placed around the bottle or other article to be protected and the whole incased or inclosed in an outside box or wrapper, the latter serves to prevent the raised portions or 55 ribs of the protector from flattening out when subjected to pressure, thus maintaining their elasticity or degree of rigidity.

Having thus described my invention, what I claim as new, and desire to secure by Letters 60 Patent, is—

1. The bottle A, having thickened portions *b*, in combination with the packing C, having the ridges *a* coincident with or adjacent to said thickened portions *b* of said bottle, substantially as and for the purpose set forth.

2. The bottle A, having thickened portions *b*, in combination with the packing C, having ridges *a* adjacent to said thickened portions, and the box B, substantially as described.

CHAS. B. HESTON.
